Baldwin & Wright*

UNITED STATES PATENT OFFICE.

FERRIS P. HARKER, OF BRIDGEPORT, CONNECTICUT.

COMBINATION KITCHEN UTENSIL.

Application filed February 18, 1926, Serial No. 89,166. Renewed August 1, 1928.

This invention relates to a combination tool which has for its object to provide a simple, practical, compact, and inexpensive device which can be manufactured readily and is applicable to many different purposes. This device combines a large number of tools which are usually provided separately for use about the household, and the article is so compact that it takes up no more room than the usual single tool. It is constructed in a simple manner whereby the various parts may, with few exceptions, be stamped from sheet metal and bent into the desired shape.

Although the illustration and description disclose the preferred embodiment of the complete tool, yet it is obvious that certain features may be omitted without modifying the action of certain other elements and various forms of the device may be made by varying the number of tools embodied in the complete device.

Further objects of the invention will be apparent from the following detailed description and will be set forth in the appended claims.

In the drawings:

Fig. 1 is a side elevation of the complete tool,

Fig. 2 is a top plan view of the same,

Fig. 3 is a longitudinal section on the line 3—3 of Fig. 2,

Fig. 4 is a perspective view of one end of the device showing the parts in extended operative position,

Fig. 5 is a section on the line 5—5 of Fig. 4,

Fig. 6 is a section on the line 6—6 of Fig. 3, and Fig. 7 is a perspective view of one of the elements of the tool detached.

The complete tool may be said to comprise a handle A, an element B forming a portion of a pan lifter and cap and lid remover, jaw elements C, a can-opening knife D, a member E which cooperates with the part B to form a pan lifter and cap and lid remover and has in addition certain other functions, a corkscrew F, a paring, coring, and scraping knife G, and a knife sharpener H.

The body member A is formed from a strip of metal bent into generally rectangular elongated form having a closed end 1, while at the other end the sides are bent toward each other at 2 and again bent to form portions 3 extending parallel with each other but separated by a very short distance. The element B is formed of a piece of metal bent

to form two parallel portions 4 which are adapted to fit outside of the portions 3 of the handle member and to be fastened thereto as hereinafter described. At one end the side portions 4 have downwardly extending members 5 connected by a cross-bar 6 to form a substantially rectangular open member. At the other end the side portions 4 have similar downwardly extending parts 7 connected by a cross-bar 8 which has a downwardly and outwardly turned projection 9.

The elements C are two in number and substantially alike in form. Each one has at its upper end an inward bend 9' which forms a shoulder, and they are then bent again to lie in planes parallel to the sides of the body of the member C. These parallel portions 10 fit outside of the portions 4 of the member B.

The can-opening knife D has a pointed end 11 and a beveled cutting edge 12. The shank of this member fits between the parallel portions 3 of the handle member A.

The member E is a sheet-metal member bent into the form shown in the drawings and provided near each edge with a stamped rib 13 for the purpose of strengthening the construction thereof and also to give the tongue member a more positive grip on the curved side of a pot or pan in the clamping action of tongue E and member B. Near one end a tongue 14 is stamped out of the metal, the purpose of which will be hereinafter explained. Near the other end of the member E two slits are made and the metal pressed out as indicated at 15, forming an opening through which passes a pivot 16, the ends of which are riveted or otherwise fastened to the side or jaw members C. The member E pivots freely about the rivet 16 and normally drops by gravity to the Fig. 3 position with the bend 17 resting against the end of the downward portion 9 of the member B.

As shown in Figs. 2 and 6, a rivet 18 passes through the ends 10 of the side elements C, through openings 19 in the side members 4 of the element B, the parallel portions 3 of the handle A, and the shank of the knife D, thereby holding all of these parts firmly together. A second rivet 20 in front of the rivet 18 passes through all of the parts mentioned with the exception of the ends 10 of the jaws C. This rivet passes through holes 21 in the sides 4 of the element B. Near the front end of the element B a stud or rivet 22 passes

through holes 23 for the purpose of stiffening and strengthening this element, this stud or rivet also acting as a rest or fulcrum point on the rim of the can when the tool is being used as a can opener.

Two rivet studs 24 and 25 pass through openings in the sides of the handle member A and on each stud is mounted a plurality of sharpening disks 26 separated by spacing washers 27. These disks are so mounted that their edges slightly overlap. Semicircular cutouts 28 in the top of the sides of the handle A register with the overlapping portions of the disks 26 so that a knife may be drawn back and forth for sharpening purposes without interference from the handle.

The corkscrew F is fastened to one side of the handle by a rivet 29 passing through an eye 30 at one end of the corkscrew. The point 31 of the corkscrew bears against the opposite side of the handle with sufficient friction (combined with the friction at its pivot point) to retain the same in its inoperative position within said handle. When it is desired to use the corkscrew, it will be swung in the direction of the arrow in Fig. 3 about its pivot 29 into open position.

The cutting, coring, and scraping member G is formed of a piece of sheet metal which has at one end side portions 32 adapted to embrace the outsides of the member A, and ears 33 are folded over into engagement with the inside of these same side bars so that the member G may have a sliding movement back and forth on the handle member. The body of this member G intermediate the side portions 32 is bent upwardly at 34 and also engages the inside of the sides of the handle. This mounting permits the member G to be slid in either direction, and when extended in operative position as shown in Fig. 4, it is firmly held against any oscillating movement. When the member G is in extended position as shown in Fig. 4 and the corkscrew is depressed to its closed position, the point 31 of the corkscrew will lie against the bent-up portion 34 of the member G and hold it firmly in its extended position. Also when the member G is in closed position and the corkscrew is depressed to its inoperative position, the portion of the eye 30 comes in such firm frictional contact with the bent-up portion 34 of the member G that the part is held against any accidental displacement towards its operative position. This member G has a cutting or scraping smooth edge 35, a serrated edge 36, a sharp point 37, and a paring or scraping knife 38 formed by cutting a slit in the body of the member and pressing out the metal slightly on one side of the slit.

It is not believed to be necessary for the purposes of understanding the invention to describe in detail the manner of its assembly. It is, however, desirable to point out the manner in which the complete tool is employed

for various purposes. The operation of the member G and the corkscrew F will be apparent from what has been said above. The manner of using the knife sharpener H is also clear since it is simply necessary to hold the tool firmly against a support by one hand and draw the knife across the sharpening disks 26 with the other hand in the usual manner.

When it is desired to use the tool for lifting a pot or pan, the tool is held in the hand in the position shown in Fig. 1 and the depending portions 5 with their connecting cross-bar 6 of the element B is placed on the inside of the pot or pan. The member E which may pivot to various positions will then engage the outside of the pot or pan regardless of its particular curvature. It will be found that if the outer end of the handle is pressed downwardly slightly, it is only necessary to lift the whole since the weight of the article being lifted will cause a clamping action between the portion of the member E and parts 5 and 6 of the member B. It is not necessary to exert any gripping action with the hand and the greater the weight of the utensil being lifted, the more firmly it will be held by the tool.

If it is desired to remove a bottle cap or vacuum lid from a jar, the tool is turned so that the member E rests upon the cap or lid while the lip 6 engages under the edge thereof. The handle is then moved in just the opposite direction to its movement when used as a pan lifter and the cap will be readily removed.

The use of the can-opening knife D will be apparent to anyone who has used can openers of the usual character.

The use of the pressed-out prong 14 for removing the paper tops from milk bottles, may be described as follows. When the parts are in the Fig. 3 position, the hand of the user is moved downward over the handle so that the little finger comes against the left-hand side of the member E, after which it will be obvious that the prong 14 may be forced into the paper cap and the same readily removed.

It is obvious that certain of the features of this device may be used in slightly varying combinations and may be omitted without directly affecting the operation of the other elements. The corkscrew and member G can, of course, be omitted without modifying in any way the operation of the remaining elements. It is to be understood that the invention is in no way limited by the above detailed description of the complete tool in its preferred form, but that it comprises all features and their equivalents which lie within the scope of the following claims.

I claim as my invention:

1. A combination tool comprising a body portion, a member attached thereto and hav-

ing a portion bent at an angle to the body, jaws carried by the body portion, and an element pivotally supported by said jaws and coacting with said bent portion to form a 5 vessel lifter and a cap remover.

2. A combination tool comprising a body portion, a member attached thereto and having a portion bent at an angle to the body, jaws carried by the body portion, and an 10 element pivotally supported by said jaws and coacting with said bent portion to form a vessel lifter and a cap remover, said member having a projecting portion acting to stop the pivotal movement of said element in one 15 direction.

3. A combination tool comprising a body portion having its sides terminating at one end in free portions, a member having sides fitting outside said free portions and having

a portion bent at an angle to the body, jaws 20 fitting outside the sides of said member, and common fastening means to secure together the body, the member, and the jaws.

4. A combination tool comprising a body portion having its sides terminating at one 25 end in free portions, a member having sides fitting outside said free portions and having a portion bent at an angle to the body, jaws 30 fitting outside the sides of said member, common fastening means to secure together the body, the member, and the jaws, and an element pivotally supported by said jaws and coacting with said bent portion to form a vessel lifter and a cap remover.

In testimony whereof, I have hereunto subscribed my name.

FERRIS P. HARKER.
